UNITED STATES PATENT OFFICE.

ANTON C. SENSOV, OF LA PORTE, INDIANA, ASSIGNOR TO U. S. SLICING MACHINE COMPANY, OF LA PORTE, INDIANA, A CORPORATION OF INDIANA.

SHARPENER FOR SLICING MACHINES.

Application filed May 25, 1925. Serial No. 32,753.

This invention relates to mechanism for sharpening the rotary disk knives of slicing machines, and has for its object the provision of improved means for preventing rotation 5 of the longitudinally sliding bearings for the sharpener spindles.

The invention is exemplified in the combination and arrangement of parts shown in the accompanying drawings and described in 10 the following specification, and it is more particularly pointed out in the appended claims.

In the drawings,

Fig. 1 is a horizontal section through the casing of a sharpener showing one embodiment of the present invention applied thereto.

Fig. 2 is a rear view of the sharpener with the cover plate removed.

The form of sharpener illustrated is similar to that disclosed in Patent No. 1,039,210, 20 granted to Hendrik Stukart, September 24, 1912. In that patent a pair of grinder spindles is provided which have longitudinal sliding movement to carry the grinders toward and away from the knife. As illustrated in Fig. 3 of the drawings, the bearings for the spindles slide longitudinally and are prevented from rotation by a pin 35, which travels in a groove 36 formed in the sliding spindle. It has been found in practice that this 30 arrangement in some cases offers sufficient resistance to the longitudinal movement of the spindle to interfere with the best operation of the device. It is noted that the bushing is under spring tension and is moved by a cam operating at the end of an arm 59. This cam produces considerable torsion on the bushing so as to cause it to bind against the pin 35 and thus interfere with the free movement of the bushing in a longitudinal direction. The present invention overcomes this 40 difficulty and at the same time provides a device which greatly facilitates the assembly of the parts and one which will not be affected by wear.

In the drawings the numeral 10 designates a casing supported by a standard 11, which is mounted on the slicing machine frame in the usual manner. The frame 10 is provided 50 with a front plate 12 having sleeves 13 and

14 formed thereon. The sleeve 13 is provided with a collar 15, in which a bearing bushing 16 is slidably mounted. The collar 15 may be rotated in the sleeve 13 and locked in different positions for changing the angular position of the bushing 16, as explained in the Stukart patent referred to above. The sleeve 14 is also provided with a collar in which the bearing bushing 17 is slidably mounted. A spring 18 normally presses the bearing bushing 16 and the grinder spindle 19 shown therein forwardly or outwardly from the plate 10. A similar spring 20 tends to retract the bushing 17 and grinder spindle 17' journaled therein. The spindle 19 carries a grinder 19' at the outer end thereof and the spindle 17' carries a grinder 17'' at its outer end. By this arrangement the two grinders are yieldingly drawn toward the slicing machine knife from opposite sides 70 thereof. Cam mechanism is provided for pressing the springs 18 and 20 to force the sharpeners away from the knife. This mechanism includes a disk 21 having cam surfaces 22 and 23 for engaging cam rollers 24 and 25, respectively. The cam disc 21 is secured to a sleeve 21' journaled on a shaft 21''. A handle 21''' is secured to the sleeve 21' for rotating the cam disc. The cam roller 24 is carried on an arm 26 formed integral with a split 80 collar 27, which is clamped upon the end of the bushing 16 by a screw 28. The cam roller 25 is carried on an arm 29, which is clamped to the bushing 17 by a screw 30. Formed integrally with and extending upwardly from the arm 26 is a post 31, and a similar post 32 extends upwardly from the arm 29. A sleeve 33 is mounted on the top of the post 31 and is pivotally attached thereto by a pivot screw 34 threaded into the end of the post 31 and provided with a stop shoulder to prevent the screw from binding on the sleeve 33. In this way the sleeve 33 is free to swing 90 about the screw 34 as a pivot. A sleeve 35 is similarly mounted by means of a screw 36 on top of the post 32. A pin 37 is freely slidable in the sleeves 33 and 35 so that the pin holds the sleeves in longitudinal alignment, but permits longitudinal movement in the direc- 100

tion of their axis. It will be apparent that by this arrangement the bearing bushings 16 and 17 will be held against rotation in their respective collars, but will remain free to 5 slide therein under the action of the springs 18 and 20 and the cam 21. The sliding movement of the two bearing bushings may take place separately or simultaneously, since the telescoping action of the sleeves 33 and 35 on 10 the pin 37 will permit independent longitudinal movement of the bearing bushings. The arrangement will not interfere with the adjustment of the collars which hold the bearing bushings in place since the sleeves and pin do 15 not in any way interfere with the position of the ends of the bearing bushings, but merely hold them against rotation. In practice it has been found that the arrangement will operate substantially indefinitely without showing 20 wear and without interfering in any way with the free longitudinal movement of the bearing bushings.

It has also been found that the arrangement is more economical to manufacture because 25 of the fact that it facilitates assembly of the parts. Heretofore considerable time has been required to fit and adjust the key and slot arrangement previously used for preventing rotation of the bearing sleeves. The present 30 arrangement can be much more quickly assembled without the necessity of fitting and adjusting so that there is considerable saving in the time required for the manufacture of the device.

35 In operation, the grinder is supported on the slicing machine with the grinder disc 19' adjacent the beveled edge of the knife and the grinder disc 17" adjacent the straight side of the edge. The grinder discs are held away 40 from the knife by the cam 21 which is rotated to bear against the rollers 24 and 25 and compress the springs 18 and 20. When it is desired to sharpen the knife, the handle 21''' is moved to a position to release the cam roller 45 24 to permit the disc 19' to engage the beveled edge of the knife. The knife is then rotated while in contact with the grinder disc 19' to sharpen the knife. Further movement of the handle 21''' will then release the cam roller 50 25 to permit the disc 17" to engage the straight side of the knife edge and remove any burr formed by the grinding operation. The handle is then returned to the left away 55 from the position shown in the drawing to retract both stones from contact with the knife.

I claim :

60 1. In combination, a pair of rotary spindles, longitudinally movable bearing bushings for said spindles, and means for preventing rotation of said bushings, said means comprising an extensible arm having the opposite ends thereof pivotally connected with said bearing bushings.

65 2. In combination, a rotary spindle, a lon-

gitudinally movable bearing bushing for said spindle, an arm having one end pivoted to said bushing by means of a pivot extending transversely to the axis of said spindle, and a pivotal support for the other end of said arm, said arm being extensible to compensate for changes in distance between the pivotal connections therefor during longitudinal movement of said bearing bushing.

70 3. A sharpener for slicing machines comprising a spindle having a grinder mounted thereon, a longitudinally movable bushing in which said spindle is journaled, an arm for moving said bushing and spindle in one direction, an arm pivotally connected with said bushing, and means co-operating with said arm to hold said bushing against rotation.

75 4. A sharpener for slicing machines comprising a spindle, a grinder mounted on said spindle, a longitudinally movable bearing bushing in which said spindle is journaled, a spring for moving said bushing and spindle in one direction, a cam for moving said bushing against the force of said spring, an extensible arm pivotally connected with said bushing, and means co-operating with said arms to hold said bushing against rotation.

80 5. A sharpener for slicing machines comprising a spindle, a sharpener mounted on said spindle, a longitudinally movable bushing in which said spindle is journaled, a spring for urging said bushing in one direction, an arm secured to said bushing and projecting therefrom, a cam for engaging said arm to move said bushing against the force of said spring, an extensible arm pivotally connected with said first-mentioned arm and means co-operating with said extensible arm to hold said bushing from rotating.

85 6. In a sharpener for slicing machines, a longitudinally movable bushing, a grinder spindle journaled in said bushing, a shiftable support for said bushing, an extensible arm pivotally connected with said bushing, and means co-operating with said arms for holding said bushing against rotation.

90 7. A sharpener for slicing machines comprising a pair of longitudinally movable grinder supports, a cam for moving said supports, and an extensible arm connected with said supports by pivots having their axes arranged transversely to the direction or movement of said supports.

95 8. A sharpener for slicing machines comprising a pair of grinder spindles, longitudinally movable bearing bushings for said spindles, a spring for each of said bearing bushings an arm for moving said bearing bushings against the force of said springs, and an arm connected with said bearing bushings by means of pivotal connections extending transversely to the axes of said bearing bushings respectively, said arm having telescoping portions to permit independent longitudi-

nal movement of said bearing bushings while preventing rotation thereof.

In testimony whereof I have signed my name to this specification on this 20th day of

5 May, A. D. 1925.

ANTON C. SENSOV.
